UNITED STATES PATENT OFFICE.

WILLIAM C. STEWART, OF SWAMPSCOTT, MASSACHUSETTS, ASSIGNOR, BY MESNE ASSIGNMENTS, TO UNITED SHOE MACHINERY COMPANY, OF PATERSON, NEW JERSEY, A CORPORATION OF NEW JERSEY.

METHOD OF PULLING OVER BOOTS AND SHOES.

1,118,966.

Specification of Letters Patent.

Patented Dec. 1, 1914.

Original application filed November 14, 1906, Serial No. 343,458. Renewed May 3, 1913, Serial No. 765,395. Divided and this application filed June 25, 1914. Serial No. 847,312.

To all whom it may concern:

Be it known that I, WILLIAM C. STEWART, a subject of King George V of Great Britain, and resident of Swampscott, county of Essex, 5 and State of Massachusetts, have invented an Improvement in Methods of Pulling Over Boots and Shoes, of which the following description, in connection with the accompanying drawings, is a specification, like letters 10 on the drawings representing like parts.

The invention to be hereinafter described relates to a method of pulling over the uppers of boots and shoes preparatory to the lasting operation.

15 In preparing for the "pulling over" operation, the insole is preferably first applied and secured to the last, as by tacks or the like, and then the upper is assembled upon the last, being usually secured thereto temporarily at the heel by a fastener driven therethrough and into the last, while the edge portions of the upper and the parts within it extend loosely about the last.

Prior to the present invention, in pulling 20 over by hand, it has been customary for the operative to jack the assembled last and shoe parts sole uppermost and then by the use of ordinary hand lasting pincers draw the upper stock, lining, and box toe over the toe end of the last and insole and to tack the upper to the insole at substantially the center of the toe. While the upper is being thus drafted forwardly at the toe, the operative maintains the middle finger of his left 25 hand in touch with the tip line of the upper and attempts, by sense of touch alone, to pull the upper so that the tip line will be properly positioned across the last. He then seizes the upper stock, linings and box toe at 30 one side of the toe, sometimes slightly forward of the tip line, and drafts said side forwardly and upwardly over the insole where it is temporarily secured by tacks, usually one at each side of one tip line. The other 35 side is then pulled over and tacked in a similar manner. During these operations the operative continues to use the sense of touch to determine the position of the upper upon the last. Frequently after the pulled 40 over shoe is taken off the jack and turned over for inspection, some or all of the tacks have to be withdrawn and the upper again pulled over to draft the upper stock prop-

erly and position the upper correctly upon the last.

55 In the old hand method of pulling over, and in the various attempts that have heretofore been made to improve thereon, the upper has been drafted or stretched while wrapped about the last or in engagement with the curved top, side, and end toe portions thereof, so that the resulting frictional resistance to any relative movement of the upper and last has interfered with a proper distribution of the stretching force to all 60 parts of the upper between the points where the force was applied. These prior methods have dictated also that the longitudinal and transverse stretch of the upper should be carried out and completed before the drafted 65 upper could be inspected and corrections made for any improper position of the upper on the last, thereby frequently necessitating withdrawal of the securing tacks and repetition of the operations.

75 With these and other matters in mind, the aims and purposes of the present invention are to provide a method of pulling over whereby the upper may be stretched before it is wrapped about the last and when lying 80 in substantially a single plane and may then, while under the stretching tension, be carried about the contour at the toe portion of the last, all as fully disclosed in the prior application of William C. Stewart, Serial 85 No. 343,458, filed November 14, 1906, renewal Serial No. 765,395, May 3, 1913, of which this is a division.

The term "single plane" is herein used to 90 designate that position assumed by the upper when it is assembled on the last at which time the upper edges extend outward from the last at one side of the bottom thereof and the upper touches, if at all, only the top of the curved toe portion of the last, and not the curved surfaces at the sides of the toe portion. For convenience of description also, the term "upper" is herein used in its broad sense and includes not only the upper stock or material, but also the parts, such 95 as the lining, box toe, and the like that are associated with it.

In practising the invention, the present method contemplates stretching the upper both longitudinally and transversely either 100 in the sequential order stated or otherwise,

but in the present exploitation, the method will be described as carried into effect by first stretching the upper longitudinally to thereby properly draft the upper and position it on the last with the tip line in desired location and thereafter stretching it transversely. The upper being thus longitudinally and transversely drafted and positioned on the last and while still under tension, is wrapped about the last or "laid to the wood" with its edges adjacent the insole, whereupon it is fastened in place, all as will hereinafter more fully appear.

An important advantage of the present invention consists in imparting to the upper the full stretch or draft desired while the fore-part of the upper is wholly at one side of the plane of the bottom of the last, so that from the heel and along the shank portions the upper is uniformly drafted or under a stretching tension and, when the fore-part of the upper is carried about the toe portion of the last a desired proper fullness is provided at the shank. Other characteristics of the present invention will be described hereinafter and be then defined by the claims.

In the drawings which indicate a series of steps constituting one mode of practising the present invention, Figure 1 shows in plan view, a last with the upper assembled thereon and stretched longitudinally and transversely while in a single plane; Fig. 2 is a cross-section on the tip line of Fig. 1 showing the upper stretched transversely in a single plane over the top curved portion of the last; Fig. 3 is a cross-section similar to that of Fig. 2 showing the previously stretched upper as having been wrapped about the last, its edge carried into close relation with the insole, and secured in place by suitable fasteners; Fig. 4 is a side elevation partly in section, showing one form of last support and a practical embodiment of means for drafting the upper longitudinally while in a single plane; Fig. 5 is a cross-sectional elevation showing the toe portion of the last in section and one form of means for stretching or drafting the upper transversely in a single plane.

As hereinbefore stated, the present invention is characterized in its generic sense by imparting to the upper such stretch as is desired while the upper is substantially in a single plane and thereafter placing the stretched upper about the toe portion of the last. The plane in which the upper is stretched before it is wrapped or placed about the toe portion of the last, is located at one side of the plane of the bottom of the last, and in case the last is supported sole downward, this plane of stretch will be above the plane of the bottom of the last.

In Figs. 1, 2 and 3, the procedure or steps 65 of the present method are indicated as be-

ing performed while the last is sole downward, and in this instance the plane in which the upper is stretched will be above the plane of the bottom of the last; but should the last be sole uppermost, the plane in which the upper is stretched would then be below the plane of the last bottom. Therefore, in referring to the plane in which the upper is stretched as being at one side of, or above the plane of the last bottom, 75 the meaning is that the plane of upper stretch is at that side of the plane of the last bottom which ordinarily constitutes the top portion of the last fore-part.

When the upper 2 and last 1 are assembled, as in Fig. 1, the edge portions 3 of the upper extend or project laterally over and from the last, substantially as indicated and above the plane of the bottom of the last. This is substantially the natural position assumed by the upper when assembled on the last, at which time the forepart of the upper touches, if it touches at all, only the top of the toe portion, and the present invention contemplates that while in substantially this position the upper shall be stretched or drafted. This step in the series is indicated in Fig. 1, wherein the projecting edge of the upper is shown as seized at the end of the toe and at each end of the tip line and by relative movement of the holding means, such as the grippers 4 and 5, and the last 1, the upper has been stretched or drafted while extending substantially in a single plane at one side of the plane of the last bottom.

This stretching of the upper in a single plane is further exemplified by the cross sectional view, Fig. 2, wherein the grippers 5, one at each side of the toe portion of the uppers, are indicated as imparting to the upper 2 its transverse stretch. It is to be noted that at this time the upper 2 touches only the top of the curved toe portion of the last 1, and in some cases may not touch the last at all, so that little or no frictional resistance between the last and upper is incurred in imparting to all parts of the upper between the points of application of stretching force a proper stretch or draft.

In the preferred method constituting a single embodiment of the invention, the upper is first stretched longitudinally, one effect of which is, in addition to imparting the desired longitudinal draft, that the upper can be and is correctly positioned longitudinally of the last to place the tip line properly, and thereafter the upper is stretched transversely, both of said stretching actions being performed while the upper 125 is still in a single plane at one side of the plane of the last bottom. Since the upper is thus treated in the single plane at one side of the last bottom, the longitudinal pull from the toe along the shank to the heel is 130

exerted with substantial uniformity upon a smooth unfulled upper, so that when the forepart is thereafter carried about the toe portion of the last, a proper fullness at the shank is furnished as is desired in some forms of boots or shoes. After the upper has been thus stretched or drafted in the single plane, it is carried about the toe portion of the last and its edges placed adjacent to the insole 6, Fig. 3, whereupon the upper is secured in place, as by tacks or otherwise.

The relative movements of the last and stretching means, such as the grippers 4 and 5, may be variously effected in carrying out the steps of the method, but in the present instance, such relative movements are secured preferably as pointed out by said prior application, wherein after the grippers have seized the edges of the upper at the toe portion, the longitudinal draft is imparted by movement of the last heelward and the transverse draft by movement of separation of the grippers at the sides of the toe portion. One form of means for thus practising the present method is fully set forth in said prior application, and is herein briefly described in connection with Figs. 4 and 5.

The last 1 with the upper 2 assembled thereon, as hereinbefore explained, may be sustained upon a suitable support, as indicated in Fig. 4, wherein the heel portion of the last is seated in a heel rest 40 and between arms 44 of a heel support carried by the rods 30 adapted to yield in response to heelward movement of the last, as fully described in said prior application, and the ball of the last is placed upon wings 21 of a ball support with the end of the toe of the last resting against a positioning stop 52. Side positioning stops 54, Fig. 5, may be further provided for engaging the last. The toe stop 52 is preferably V-shaped to center the tip of the last toe thereagainst, and is supported by the link 122 pivoted to an arm 124 which is itself movable, as fully described in said prior application, to set the last heelward after the grippers have seized the upper to thereby impart to the upper its longitudinal draft. The toe positioning stop and the side positioning stops are moved from their last supporting positions as the grippers, to be hereinafter described, carry the stretched upper about the last, but as these features of structure are fully described in said prior application to which reference may be had for a full disclosure of the mechanism, their further description herein is unnecessary. The last with the upper assembled thereon having been placed upon its support, it is to be seized by the pulling over means, and, with respect to the toe end pulling over means, held while the last is set heelward. A form of toe end pulling over means may comprise

gripper jaws, two pairs being herein shown, one pair at each side of the center of the toe end, Fig. 1.

Referring to Fig. 4, one form of toe end pulling over means and operating connections is shown and will be briefly described.

Mounted to slide in the curved guide 12 is an upwardly extending support 90 which sustains a vertically arranged curved guide 92 on which is mounted the carriage 94 carrying the gripper jaws 4, of the general construction described in said prior application. The link 72 for opening and closing the jaws is connected to a lever 76, the other end of which carries a pin 80 having a pawl adapted to engage the ratchet teeth 84 on the upper portion of the carriage 94. The lever 76 is also provided with an arm 86 having a socketed end to be engaged by a push rod 104, the construction being such that upward movement on the push rod will close the jaws upon the edge of the upper placed between them and the parts will be locked in this position by the ratchet teeth 84 and a pawl 82 carried by the pin 80, all as fully described in said prior application.

When the toe gripper jaws are in open position, the surface of the lower jaw extends in a plane substantially parallel to and at one side of the bottom of the last, so that the toe portion of the upper, which when the upper is assembled on the last, extends loosely over the last in substantially a single plane, and may be readily positioned between the jaws by the operative. The toe gripping jaws 4 having been closed by the push rod 104, the toe stop 52, through the described connections, will be moved heelward to thereby stretch the upper longitudinally, substantially as set forth in said prior application.

Extending from the gripper carriage 94 is a pin 184 engaging the slotted end 180 of an actuator 178, whereby, through suitable operating means, the actuator 178 may be drawn downwardly to move the toe gripper carriage in its guideway 92 to carry the gripper jaws about the toe end of the last into substantially the dotted line position as indicated in Fig. 4.

Mounted at the upper portion of the guide 92, is a fastener presenting mechanism which may be substantially of the character described in said prior application, for presenting fasteners to a fastener driving means or driver 300 which is carried by a sleeve 302 pivotally mounted on the gripper carriage 94, the construction being such that as the gripper carriage is moved downwardly on its curved guide 92, the driver 300 carries a fastener into position beneath the edge portion of the then pulled over upper, substantially as indicated in dotted lines, Fig. 4, and as more fully described in said prior applications. When the driver

has reached its driving position, it is acted upon by a hammer 274 in the manner fully described in said prior application, to drive the fastener through the upper and into the insole to secure the upper in place.

The side or transverse stretching and pulling over means may be substantially similar to the toe pulling over means hereinbefore briefly described and as indicated by Fig. 5, 10 wherein the side gripper carriage 60 for each of the side grippers is mounted for movement upon the curved guide 58 through the medium of an actuator 176 similar to the actuator 178, already described in connection with the toe gripper mechanism. Like the toe gripping mechanism also, the side gripper carriages have each mounted thereon, a fastener driver 300 which takes a fastener from the source of supply, as indicated in Fig. 5, and carries it to driving position as indicated in Fig. 3, whereupon the hammer 274, like that of the toe gripper mechanism, effects driving impulse to the driver to insert a fastener through the then pulled over upper, and into the insole. This brief outline of a particular means for carrying the present invention into effect will be sufficient in connection with the disclosure thereof as contained in the prior application hereinbefore mentioned, and of which the present application is a division.

It will be understood that when the last is placed with its bottom upon the heel and ball supports and between the toe and side 35 positioning stops heretofore described, the upper, which is then extended loosely over the last, is smoothed out by the operative and is placed upon the lower jaws of the open side and toe grippers. The upper having been placed in this position, the grippers are preferably all closed simultaneously by the operative by actuating the two sets of push rods 88 and 104. After the grippers are thus closed upon the stock, the upper 40 should be stretched and carefully positioned on the last and finally its margin placed adjacent the insole in position to be secured thereto. Much better results are obtained by stretching the upper before it is placed 45 entirely about and in contact with the curved portion of the fore-part of the last than if the stretching were done after this operation, as by the former method frictional contact with the last is eliminated and 50 more uniform results secured. This can be accomplished by any suitable form of mechanism wherein the stretching is performed in advance of and before the completion of the overlapping operation. The upper is preferably first stretched and positioned longitudinally, as by heelward movement of the toe stop 52, and then it is stretched transversely by separating movement of the grippers 5, Fig. 5, through a further actuation of their 55 push rods 88, as fully set forth in said prior 60 65

application, that is, the upper is stretched both longitudinally and transversely while it extends in substantially a single plane at one side of the plane of the last bottom, so that during such stretching action the stretching force is applied with substantial uniformity to the upper between the points of application thereof. During this stage of the procedure, the upper remains smooth from the toe through the shank to the heel 70 portion by reason of the shape of the upper, and the plane of action of the stretching force, so that when the forepart of the stretched upper is carried downward or in a direction toward the plane of the last bottom, the heel and fore-part of the upper are relatively moved to produce a bend or fullness at the shank for subsequent lasting at this point. The upper while stretched as described, is carried about the toe portion of the last and secured in position to the insole.

The particular means employed for carrying the present invention into effect forms no essential part thereof, but the means briefly described and more fully exemplified in said prior application, constitutes a good and convenient form of such mechanism.

What is claimed is:—

1. The method of pulling over boots and 95 shoes, which consists in stretching the upper while extending in substantially a single plane, and carrying the stretched upper while under tension about the toe portion of a last.

2. The method of pulling over boots and 100 shoes, which consists in stretching the upper both longitudinally and transversely while extending in substantially a single plane, and then placing the stretched upper about 105 the toe portion of a last.

3. The method of pulling over boots and 110 shoes, which consists in stretching the upper longitudinally and completing the lengthwise position of the upper on the last while in unobstructed view, then stretching the upper transversely and carrying the stretched upper about the toe portion of the last.

4. The method of pulling over boots and 115 shoes, which consists in stretching the upper in substantially a single plane and completing the lengthwise position of the upper on the last, then stretching the upper in substantially the same plane transversely, and 120 thereafter carrying the stretched upper about the toe portion of the last.

5. The method of pulling over boots and 125 shoes, which consists in stretching the upper while extending in substantially a single plane, and carrying the upper while in such stretched condition about the toe portion of a last, and then securing the overplaced upper in position.

6. The method of pulling over boots and 130

shoes, which consists in stretching the upper both longitudinally and transversely while extending in substantially a single plane, then placing the stretched upper about the toe portion of a last, and then securing the previously stretched and overplaced upper in position.

7. The method of pulling over boots and shoes, which consists in first seizing the upper at its edge in the vicinity of the toe while extending in a single plane, then relatively moving the last and upper longitudinally to stretch the upper while in said plane and to position the tip line, and then carrying the upper about the toe portion of the last.

8. The method of pulling over boots and shoes, which consists in seizing the upper at its edges in the vicinity of the toe while extending in a single plane, then relatively moving the last and upper longitudinally to stretch the upper and position the tip line longitudinally, then stretching the upper transversely, and then carrying the stretched upper about the toe portion of the last.

9. The method of pulling over boots and shoes, which consists in first seizing the upper at its edge in the vicinity of the toe while extending in a single plane, then relatively moving the last and upper longitudinally to stretch the upper while in said plane and to position the tip line, and then carry-

ing the upper about the toe portion of the last, and then securing the upper in position.

10. The method of pulling over boots and shoes, which consists in stretching the upper longitudinally in a plane at one side of the plane of the last bottom and thereafter carrying the upper while thus stretched about the toe portion of the last.

11. The method of pulling over boots and shoes, which consists in stretching the upper transversely in a single plane, positioning the upper longitudinally on the last and then carrying the stretched upper about the toe portion of the last.

12. The method of pulling over boots and shoes, which consists in stretching the upper in a plane at one side of the plane of the last bottom, then while maintaining the upper in the stretched condition relatively moving the fore-part and heel portions of the upper in a direction toward the last bottom to full the upper at the shank portion, and securing the stretched upper in place.

In testimony whereof, I have signed my name to this specification, in the presence of two subscribing witnesses.

WILLIAM C. STEWART.
